(76) Inventor: **Isaiah Jennings**

Eduard Penning

No. 528

The schedule referred to in the Batten Patent and made a part of the same containing a description of the same in the words of the said Batten Penning himself of the improvements in the apparatus for generating and condensing steam for steam engines and of traps in the process of distillation. To all whom it may concern, be it known that Eduard Penning of the city of New York in the State of New York has invented an improved apparatus to be used as a boiler or condenser for generating or condensing steam in steam engines and traps of various kinds in distillation, and I distinctly declare that the following is a full and exact description thereof. The boiler or condenser may be made in any form which may be desired, but in general I prefer to make them flat or planar, excepting that they must have protuberances and indentations on their surfaces resulting from their particular construction, which is as follows, Metal plates are taken and there are to be so many of them by sawing, stamping or otherwise, that their whole surfaces on each side shall present alternate convexities and concavities regularly distributed, and so that when two such plates are laid upon each other, their convex parts shall come into contact with each other, for a distance necessary, so the touching points may be about four inches apart, but this distance will vary according to the strength of the metal and the pressure to which it is to be subjected, at each of these touching points the metal is to be prepared to receive stay-bolts by which the plates are to be secured together, as well as at their edges, the cavities between the plates will then communicate freely with each other and will form a space

more receptacles for tea, &c. These double plates may be
bent into a cylindrical or other form if desired, ^{or any shape} & then may be placed side by side, & be duly exposed to the action of the heating or refrigerating agents, as into
the ready, understood, & approved competent engines, the
situations where water is scarce, or where other consider-
ations may render it proper, I intend to use air as a con-
densing agent, & forcing it over the surfaces of the combined
plates by means of a revolving fan or other blowing ap-
paratus. What I desire, as my invention, is, a method
to secure my Patent, is, the making of boilers or
condensers, of double sheets of metal, bent in the form
therein described, and united together by stays, bolts, &c
on the principle and, for the purposes set forth.
